Serial No. 557,725

12 Claims. (Cl. 196—62)

1

The instant invention relates to the production of toxic oils employable as fungicides, insecticides, and for any other service to which toxic oils may be put, and is a continuation in part of our application Serial No. 469,722 for "Process of providing useful products," filed December 21, 1942, pending herewith, and which is now abandoned, as to all matter common to the two applications.

More especially the instant invention relates to the production of toxic oils from mixtures of petroleum fractions characterized by ring structure content. Among such starting materials may be mentioned mixtures of petroleum fractions characterized by ring structure content recovered from petroleum fractions by well known extraction methods including extractive distillation and solvent extraction. Also may be mentioned mixtures of petroleum fractions characterized by ring structure content as flowing from thermal and/or catalytic treatment of certain petroleum fractions which includes petroleum fractions having ring structures induced in the course of thermal and/or catalytic treatment, as for example, having ring structures induced in the course of one or more thermal and/or catalytic treatments of unusual length, say for periods of from 1-10 hours or more.

An object of the instant invention is the production of toxic oils from the aforesaid petroleum fractions or others whereby to provide oils of the preservative type, as for example preservative wood impregnants conforming to specifications extant or acceptable to the trade consuming such oil materials.

Another object of the instant invention is the provision of preservative wood impregnants having boiling ranges and residues in accordance with published specifications and/or in accordance with consumer preference.

Another object of the instant invention is the cracking, reforming, modifying, converting and/or transforming of mixtures of hydrocarbons whereby to induce toxicity.

Still another object of the instant invention is the induction of commercially usable toxicity in the presence of a gas or gaseous mixtures of extraneous source.

Another object of the instant invention is the unveiling of latent toxicity in mixtures of petroleum fractions having inherent but inhibited toxicity.

Yet another object of the instant invention is the provision in the overall beneficiated material

2

of that percentage of newly induced fractions boiling below 210° C. which, in view of attendant reactions, is conducive to the induction of toxicity in other fractions of the material under treatment.

Another object of the instant invention is the induction of additional toxicity into fractional parts of the once beneficiated starting material under specific controls of process variables.

10 A specific object of the invention is the cracking, transformation, reformation, conversion and/or modification of relatively high boiling petroleum oils characterized by molecular structures of cyclic materials content having inherent but inhibited toxicity whereby to provide said molecular structures of cyclic content as reformed materials exhibiting a more pronounced toxic value.

Still another object of the present invention is 20 the conversion of substantially non-toxic "petroleum type aromatics" into materials more closely approaching the highly toxic "coal tar aromatic type," as more fully set forth in the following.

Still another object of the present invention is 25 the conversion of "petroleum type aromatic" material of a relatively narrow boiling range into material of relatively wide boiling range more closely approaching the characteristics of "coal tar aromatics" by a process wherein the control is evidenced by, among other things, the percentage of newly formed aromatics found in certain fractions of the beneficiated material.

In the past wood preservative oils of the high 30 temperature coal tar derived type have been employed in quantities greatly exceeding the total of all other wood preservative oils. From the standpoint of availability of said coal tar as the parent product of wood preservative oils, it is annually produced in this country under normal conditions to the extent of five hundred million to six hundred million gallons. This quantity of coal tar is capable of yielding an amount of highly effective wood preservative oil which would make this country self sufficient in its wood preservative requirements. However, due to the fact that when a wood preservative distillate (creosote) is recovered from coal tar there remains in the still a residue (pitch) which, at best, is a low priced product and which, at worst, is a seriously distress product to the end that at times it is placed in inventory rather than sold, the current method of processing coal tar leaves much to be desired. The net result of this situation obtain-

ing is that the coal tar distiller usually confines himself to that distillation recovery of creosote which would correspond to the attending amount of pitch that he can market at a profit. Accordingly, over a period of years several hundred million gallons of creosote oil have been imported into this country. That such a situation should obtain is apparently a paradox in that we annually produce a quantity of high temperature coal tar which if processed to yield creosote would make us self sufficient in that requirement. A survey of this paradox is fully outlined in an address given by no less an authority than S. P. Miller, technical director, The Barrett Company, 40 Rector Street, New York city, before the Franklin Institute, Philadelphia, Pennsylvania, in December, 1932. The economics of coal tar have not materially changed since that date.

In view of the apparent inability of the coal tar industry to provide national needs of wood preservative oils, a strong incentive is given to groups processing other types of oil to invade the lucrative wood preservative market. At the present time many types of so-called aromatic oils are produced by the petroleum industry, and the high boiling oils of aromatic content produced by this industry have for several years been tested for their wood preservative efficiency.

By the term "petroleum aromatic" as used herein and in the appended claims it is meant to include mixtures of petroleum fractions characterized by cyclic structure content and specifically various forms and types of naphthenes found in various mixtures of petroleum fractions, as for example monocyclic and polycyclic naphthenes.

The so-called petroleum aromatics which include the monocyclic and polycyclic naphthenes and unsaturated hydrocarbon have in the past been produced in very large quantities. However, very little work has been done on these materials. Such a fact is borne out on page 667, "Reaction of pure hydrocarbons," Gustav Egloff, Reinhold Publishing Corporation, 330 West 42nd Street, New York city, which states:

"Despite the fact that naphthenes or cycloparaffines are available in enormous quantities, as shown by an estimate of 100,000,000 barrels present in the 1,498,000,000 barrels of crude oil which was the world's production in 1934, comparatively little work of a pyrolytic nature has been performed on individual naphthene hydrocarbons or the cycloolefins."

Several oils of cyclic structure content produced by the petroleum industry have been inspected for their toxicity to wood destroying fungi, among which may be mentioned a high boiling oil of cyclic structure content produced (1940) at the Wood River Refinery of the Shell Oil Company and which has the following inspection:

In the foregoing tabular data P. M. C. C. means 10 Pensky-Martin Closed Cup; C. O. C. means Cleveland Open Cup.

Upon evaluating the foregoing oil for its toxicity to wood destroying fungi (Madison 517), it was found that this oil did not totally inhibit 15 the growth of the fungi named at a concentration of up to and including 10%. Madison 517 is a strain of the fungus *Fomes annosus*.

It is now discovered that the oil above named 20 or other oils of cyclic structure content produced by the petroleum industry can be increased in toxicity in accordance with the process of the instant invention.

According to the instant invention, oils of cyclic 25 structure content produced by the petroleum industry are cracked, reformed, transformed, modified and/or converted to oils of a more toxic nature having characteristics more closely approaching those of high temperature coal tar oils. Stated in another manner, the end product of the 30 instant invention is acceptable to consumers of preservative wood impregnants and/or conforms in boiling range or aromatic content to previously published wood preservative specifications.

We have discovered that if the starting materials 35 are subjected to a thermal treatment in the presence of an extraneous gas at a temperature selected between the limits of about 350-600° C., the while controlling process variables as to provide in the materials of the end product boiling 40 between 210° C. and 355° C. a percentage of aromatics not substantially less than about 70%, the reformed, cracked, converted, transformed and/or modified oil boiling between about 210° C. and 355° C. will have a toxicity to wood destroying 45 fungi closely approaching or equaling the toxicity of high temperature coal tar or its wood preservative derivatives, provided (1) the specific gravities of the overall fractions within the 210-355° C. cut of the beneficiated fall about within the 50 limits shown in the appended tabular data:

	Fractions	Low Limit	High Limit
55	210-235° C.	0.829	0.9042
	235-270° C.	0.878	1.0245
	270-315° C.	0.942	1.0575
	315-355° C.	1.001	1.1175

or (2) specific gravities of the aromatics in the 60 overall fractions of the 210-355° C. cut of the beneficiated material fall about within the limits shown in the appended tabular data:

	Fractions	Low Limit	High Limit
65	210-235° C.	0.913	1.0430
	235-270° C.	0.935	1.0666
	270-315° C.	0.973	1.0033
	315-355° C.	1.027	1.1285

70 The following examples will serve to illustrate several modes of practicing the present invention.

Example 1.—A mixture of petroleum fractions characterized by a substantial content of "petroleum type aromatics" and having but slight 75

growth inhibition to wood destroying fungi, as for example, a "petroleum aromatic" type oil boiling preponderantly between 235° C. and 355° C., whose fractions 235-270° C., 270-315° C. and 315-355° C. have respectively the following specific gravities: 0.9697, 0.9989 and 1.036, is charged to a high pressure autoclave under a cold pressure of 500 pounds of hydrogen and brought up to a temperature of 495° C. where it is held for a period of one hour. The pressure reaches a maximum, of about 2200 pounds per square inch. The beneficiated material is cooled and inspected and is found to have (1) newly formed materials boiling below 210° C., and (2) an overall toxicity closely approaching or equaling the toxicity of certain high temperature coal tar wood preservatives.

Inspection of the beneficiated material discloses matters shown in the appended tabular data:

Fraction	Toxicity (Total Inhibition Point)	Specific Gravity of Aromatics	Percentage of Aromatics
0-210° C.	0.50	0.8510	40.0
210-235° C.	0.005	0.9506	100.0
235-270° C.	0.010	0.9941	100.0
270-315° C.	0.500	1.0159	100.0
315-355° C.	>5.000	1.0546	100.0

Entire five fractions approx. 0.050.

The total inhibition point (toxicity test) above noted is expressed as the percentage of the preservative by weight of medium on which tested and required to totally inhibit the growth of the fungus under test. This toxicity test is fully described on page 34 et seq. of the 1933 Proceedings of the American Wood Preservers' Association.

The starting material of the instant example has an unsatisfactory toxicity to wood destroying fungi conceivably due to certain portions of the side chains attached to the ring nuclei which probably lower water solubility. We have found by controlling the process variables as to provide in the 0-355° C. or 210-355° C. cut of the beneficiated material (1) specific gravities in aromatics in fractional parts of said cut which fall between the limits previously stated, and/or (2) specific gravities in overall fractions of the named cut which fall between the limits named in the foregoing, that this is a guarantee of, and a test for, the induction of toxicity to wood destroying fungi in the named cut or cuts which closely approaches or equals the toxicity of certain high temperature coal tars or their preservative derivatives. The controls above named, either or both, are practices by which sufficient side chains or fractional parts thereof may be removed from the highly toxic ring nuclei to insure acceptable toxicity in the beneficiated material to the wood preserving industry.

By processing the starting material of the instant example in the presence of an extraneous gas as above described, a crude material whose toxicity to wood destroying fungi is not acceptable to the wood preserving industry is at least partially converted into a material which closely approaches or equals the toxicity of conventional high temperature coal tar or certain of its oily wood preservative derivatives.

The beneficiated material is fractionated by distillation to recover as a distillate a preservative wood impregnant of induced toxic properties having 5% distilling below 210° C., more than 18% distilling above 315° C., and less than 10% residue above 355° C. It is of especial importance that the

newly formed preservative oil which flows from our controlled thermal treatment in the presence of an extraneous gas has at least about 15-20% residue above 315° C. for it is on these materials boiling above 315° C., among others, that our new oil depends for its permanency after impregnation into wood.

The materials of induced toxic properties as flowing from the process carried out under the controls above disclosed have at times substantial residual matter above 355° C. and may be used in toto as a wood preservative impregnant, or in the event it is desired to provide a preservative impregnant complying with specifications extant or of consumer preference, a wood preservative oil may be segregated from the overall beneficiated material as a stabilized residual distillate or extract, and in the event the extract has non-permissible low boiling ends, the extract may be stabilized to the necessary extent by removal of low boiling ends; or the preservative oil may be recovered from the extract as a distillate.

As illustrative of preservative wood impregnants of the oil derived type that have met with consumer acceptance, and which may be segregated from the overall beneficiated material of the instant process, the following tabular data show several published wood preservative specifications which have been accepted by the trade.

WOOD PRESERVATIVE IMPREGNANTS

Specifications

1. American Wood Preservers' Association

Example 2.—A "petroleum aromatic" oil having 6% distilling below 235° C., and boiling preponderantly between 235° C. and 355° C. is charged to a high pressure autoclave under a cold hydrogen pressure of about 475 pounds and brought up to a temperature of 490° C. within

a period of about one hour and 30 minutes. The maximum pressure is somewhat above 2100 pounds per square inch. When the named temperature is reached it is maintained for a period of 30 minutes; the heat is then cut and the beneficiated oil allowed to cool. Inspection reveals that the 210-355° C. cut of the oil heat treated in the presence of an extraneous gas is substantially as toxic as conventional high temperature coal tar creosote.

The 210-355° C. cut of the heat treated oil has the following inspection:

Fraction	Toxicity (Total Inhibition Point)	Overall Specific Gravity of Fraction	Percentage of Aromatics
210-235° C.	0.005	0.9506	100.0
235-270° C.	0.010	0.9941	100.0
270-315° C.	0.500	1.0159	100.0
315-355° C.	>5.000	1.0546	100.0

All four fractions approx. 0.050.

The 210-355° C. fraction of the beneficiated raw material is segregated therefrom by fractional distillation to provide highly toxic preservative wood impregnant as a distillate.

By providing in the beneficiated material the overall specific gravities noted in fractional parts of the 210-355° C. cut, a guarantee is secured that sufficient reforming, cracking, modifying and/or converting has been accomplished to insure the materials in the beneficiation boiling between about 210° C. and 355° C. having a toxicity comparing favorably with that found in high temperature coal tar preservative impregnants.

Example 3.—When processing the starting materials in the presence of an extraneous gas as disclosed in Examples 1 and 2, it is found that the materials boiling below and above 270° C. have a relatively high and low toxicity, respectively. It is of importance that the reformed materials boiling above 270° C. have as high a toxicity as possible to wood destroying fungi for the reason that these materials have a toxicity blanketing effect on the lower boiling materials of highest toxicity. By retreating the once processed materials boiling above 270° C. we have discovered that additional toxicity may be induced. We outline hereinafter a typical practice of this phase of our invention.

The starting material is charged to an autoclave under a cold hydrogen pressure of 500 pounds per square inch. The temperature is then raised to 480° C. and there held for a period of 45 minutes. The partially beneficiated material is allowed to cool to atmospheric temperature, and cut at 270° C. to provide a low boiling portion of relatively high toxicity and a high boiling portion of relatively low toxicity. The high boiling portion is charged back to the autoclave under a cold hydrogen pressure of 500 pounds. The contents of the autoclave are heated to a temperature of 475° C. and there held for a period of 30 minutes. The autoclave is allowed to reach atmospheric temperature and the contents discharged. The once and twice treated materials are commingled and are found to have in the materials boiling between 210° C. and 355° C. a percentage of aromatics in excess of 70%. The specific gravities of the aromatics in question fall between the limits shown in the foregoing tabular data, and the specific gravities of overall fractions in the 210-355° C. cut fall within the limits previously noted.

A preservative wood impregnant boiling predominantly between 210° C. and 355° C. and with 30% residue above 315° C. is segregated from the commingled beneficiation, and subsequent inspection reveals the fact that the segregation has a toxicity acceptable to the wood preserving industry, that is to say, a toxicity closely approaching that found in oily preservative derivatives of high temperature coal tar.

10 Instead of cutting the primary beneficiated oil at 270° C., the cut may be made at any other temperature, say at 285° C., 300° C., above or below, whereby to provide the low boiling portion as a material of relatively high toxicity and the high boiling cut as a material of relatively low toxicity. The high boiling portion is then treated at a temperature falling within the limits previously disclosed.

We have found when practicing our two-step process in the presence of an extraneous gas as disclosed in the instant example that by providing a total treatment period of not in excess of about two hours, acceptable toxicity closely approaching or equalling that of high temperature coal tar preservative products may be provided.

25 As illustrative of this mode of practice, but without inferring treatment period limitations, a period not in excess of one hour may be employed in the primary step, and a period not in 30 excess of 30 or 40 minutes, more or less, may be employed in the secondary step which retreats the higher boiling segregation. Such treatment periods have been found to give the desired results, although other periods of treatment for 35 the two steps, the total of which falls below about two hours, may be practiced.

Example 4.—A "petroleum aromatic extract" distilling 30% below 315° C. and with 40% residue above 355° C., having an aromatic and unsaturated content of 70%, a specific gravity of aromatics of 1.01 in the 270-315° C. fraction and a specific gravity of aromatics of 1.02 in the 315-355° C. fraction is charged to a high pressure autoclave and propane is pumped in to an upper 45 limit of 1000 pounds per square inch. The temperature is raised to 450° C. and held there for a period of one hour. Thereafter and without substantially lowering the temperature, the contents of the autoclave are discharged to a larger autoclave and held under a pressure of 400 pounds for 50 a period of 30 minutes. At the end of the named second period the beneficiation is cooled and inspected, and is found to have in excess of 70% aromatics in the materials boiling between 210° 55 C. and 355° C., and the fractional parts of the 210-355° C. cut have aromatics whose specific gravities fall within the limits noted in the tabular data previously shown.

The beneficiation which has newly induced 60 fractions boiling below 210° C. is fractionally distilled to provide a distillate of the wood preservative type boiling substantially between 210° C. and 355° C. Upon evaluation, the wood preservative type distillate reveals a toxicity to wood destroying fungi comparing favorably with that toxicity found in high temperature coal tar creosote.

In the two-step operation disclosed in the instant example we have found that a period of not in excess of about one hour is suitable for the primary step. Dependent upon the temperature selected within the range previously disclosed, periods of 20, 30 or 40 minutes, more or less, are acceptable. In the secondary step of this mode of 75 practicing the instant invention, we have found

that a period not in excess of about one hour is sufficient to induce the desired qualities and characteristics in all starting feed stocks. With some feed stocks periods of 20, 30 or 40 minutes, more or less, are satisfactory in the secondary step. When employing in the first stage a relatively high temperature within the range previously disclosed, and a relatively high pressure drop in the second stage, a relatively short period of treatment in the second stage will provide the desired percentage and specific gravities of aromatics.

The relationship of the high and low pressure steps may vary over relatively broad limits, as for example, the first step may be carried out at very high pressures and the second step at a pressure only slightly above atmospheric. On the other hand, if a relatively low pressure is employed in the first and high pressure step, say a pressure of about 400 pounds per square inch, then atmospheric or subatmospheric pressure may be employed in the second step.

Viewed broadly this phase of practice of our invention is not circumscribed by any definite pressures in the high and low pressure steps, but rather turns on employing a relatively high pressure in the first stage and a relatively low pressure in the second stage.

Example 5.—The Shell aromatic oil noted previously is charged to a high pressure autoclave. Methane is pumped in to an upper pressure of 900 pounds per square inch. The contents of the autoclave are raised to a temperature of 465° C. and held at that temperature for 40 minutes. Thereafter the temperature is raised to 500° C. and held at that heat tone for a period of 30 minutes. The beneficiated material is cooled and inspected and is found to have newly formed fractions boiling below 210° C., and in the materials boiling between 210-355° C. in excess of 95% aromatics. The specific gravity of aromatics in fractional parts of the 210-355° C. cut of the beneficiation fall between the limits noted in the tabular data previously shown. A toxicity evaluation of the materials boiling between 210-355° C. indicates that only about 0.5% is required for total inhibition of growth of wood destroying fungi.

We have found that when practicing our invention with a relatively low temperature step and a subsequent relatively high temperature step, either and preferably both steps being carried out in the presence of an extraneous gas, the temperatures in both steps being selected between the limits of about 350-600° C., optimum conditions are secured by providing a treatment in each step of not in excess of about one hour. If relatively high temperatures within the limits named are employed in the two-step process of dissimilar temperatures, relatively short periods in the two steps are possible, and we have found that under very severe thermal conditions within the limits named, periods of 10, 20 or 30 minutes in each step suffice to induce the desired characteristics.

Viewed broadly, this phase of our invention is not circumscribed by any definite time period, other than the upper limit above stated, but rather turns on the correct coordination of a relatively low temperature step and a relatively high temperature step, whereby to provide the desired percentage and specific gravity of aromatics and/or the desired percentage of aromatics and specific gravity of overall fractions in the end product, which thing or things in turn insure induction of toxicity closely approaching or equaling that of high temperature coal tar preservative wood impregnants.

When treating certain mixtures of petroleum fractions that have a relatively low "petroleum aromatic" content we have found the operational procedure as outlined in the following example of especial merit.

Example 6.—A recycle petroleum oil containing less than 35% "petroleum aromatics" is subjected to the processing conditions disclosed in Example 1. Upon inspection of the beneficiated material it is found that although the specific gravities of the aromatics fall within the limits previously shown, the total of aromatic content is less than 70% in the 210-355° C. cut. The beneficiated material is then extracted with liquid sulfur dioxide and the raffinate discarded. The extract is then stabilized to provide a residual as an oil of the wood preservative type boiling preponderantly between 210-355° C., and which has an overall total inhibition point to the growth of wood destroying fungi of not in excess of about 0.5%.

Although liquid sulfur dioxide is shown as the extracting agent, it is immediately obvious that other materials may be employed, as for example furfural or the like.

Instead of practicing the process in a once through treatment as disclosed in Example 1, especial toxicity induction benefits flow from dividing the beneficiation into a relatively low boiling portion and a relatively high boiling portion, and subsequently retreating separately the two fractions. The two fractions may be treated at similar or dissimilar temperatures within the range previously disclosed. When the retreated fractions are commingled, it will be found that they have a toxicity in excess of the once treated material.

In lieu of retreating both the high and low boiling portions, the low boiling portion may be retreated and then commingled with the once treated high boiling portion to provide a comminglement having a toxicity in excess of the once treated oil.

Another mode of practicing our invention resides in treating the "petroleum aromatic" containing oil in the presence of benzene, toluene, naphthalene or their derivatives. As exemplifying this mode of practice, illustratively 50 parts of the petroleum aromatic oil and 50 parts of benzene are commingled. The comminglement is then, for example, treated as in Example 1. The resultant alkylated benzene is then removed. Upon inspection, it will be found that the petroleum aromatic has a percentage of aromatics not lower than 70% and the specific gravities of the aromatics in fractional parts of the 210-355° C. cut fall between the limits noted in the tabular data previously shown. The commingling of 50 parts of the petroleum aromatic with 50 parts of benzene is for purposes of illustration only; other percentages may be used.

When the feed stock consists of a petroleum oil having a relatively low percentage of "petroleum aromatics" and unsaturates, it is advisable to first extract the oil and then treat the extract according to any of the modes of practicing our process.

Example 7.—We have discovered, as previously disclosed, that the basic reason why "petroleum aromatics" have relatively little toxicity is because of the relatively non-toxic materials (side chains or fractional parts thereof) attached to the ring nuclei which probably lower water solubility. Our previously described modes of practice of the instant invention increase toxicity by, among other things, raising the specific gravity

of aromatics and/or overall fractions by controlled side chain elimination from the ring nuclei. However, we have discovered that when shortening or removing side chains from the ring nuclei, nascent radicles are formed which may, on the one hand, further alkylate the ring nuclei, or, on the other hand, polymerize to form high boiling chain structures which boil within the range of the reformed aromatics. In either instance this is not desired, and more especially the polymerization of the nascent radicles to form relatively high boiling chain structures is not desired for the reason that they dilute the toxicity of the reformed aromatics.

We have discovered that if we will shorten or remove side chains from the ring nuclei in accordance with the instant process and within a relatively short period, and then shock cool the entire beneficiation, a certain degree of the said polymerization and/or alkylation is precluded, thus resulting in a toxicity in the cracked, transformed, reformed, modified and/or converted oil comparable to that of certain high temperature coal tar preservative oils.

When applying this mode of practice to our instant invention, we hold the treating period to not in excess of about two hours, and preferably not in excess of about one hour. When employing relatively high temperatures within the extreme upper limits of the range previously disclosed, periods of 15-30 minutes, or less, will suffice for the necessary reforming previously taught. Immediately thereafter the beneficiation is shock cooled to a temperature below about 250° C., and preferably below 200° C. by a relatively cool oil, which may be the preservative oil previously made by the process. The reformed oil is fractioned as shown above.

Example 8.—A petroleum aromatic oil, as for example, the Shell oil previously described is pumped in closed circuit through an apparatus designed to withstand high pressures and high temperatures. The pressure is maintained at 3000 pounds per square inch and the temperature at 480° C. Water gas is continuously circulated in the closed circuit at a rate of 5000 cubic feet per barrel feed stock. The oil and gas in the closed circuit are kept in circulation. At the end of about one hour or one hour and 15 minutes, the heat treated oil and water gas are continuously withdrawn with compensating admission of fresh feed oil and gas to the circuit. The withdrawal and admission of the oil and gas are regulated to provide the heat treating period above named, that is to say, about an hour or an hour and 15 minutes. Fresh water gas is pumped in with the new feed at a rate previously indicated. The withdrawn heat treated material, after separation of occluded gas, is cooled and inspected and is found to have a percentage and specific gravity of aromatics in the 210-355° C. cut falling within the limits previously disclosed. The specific gravities of overall fractional parts of the 210-355° C. cut will also be found to fall within the limits previously shown, and the toxicity of the overall 210-355° C. cut compares favorably with certain high temperature coal tar creosotes.

In previous examples, the overall feed stock has been shown as being treated. In lieu of this, the raw feed stock may be divided into two or more fractions and separately treated. As an example, the feed stock may be divided into a relatively low boiling fraction and a relatively high boiling fraction. The low boiling fraction is then treated at a relatively high temperature within

the range disclosed, and the high boiling fraction is treated at a relatively low temperature within the stated range, the periods of treatment in this instance being the same as taught previously for high and low boiling cuts, beneficiated or otherwise. If three cuts of the raw feed are made, the lowest boiling fraction is treated at the highest temperature, the intermediate fraction at an intermediate temperature and the highest boiling fraction at the lowest temperature. This teaching applies to any number of cuts into which the feed may be divided.

Viewed broadly, the product of the instant process is a transformed, reformed, modified and/or converted petroleum oil boiling preponderantly between 210-355° C. with at least about 15-20% material boiling above 315° C., having at least about 70% aromatics in the materials boiling between 210° C. and 355° C., and in the fractional parts of the oil boiling between 210-355° C., certain specific gravities as taught in the foregoing.

The pressures in the present invention are in excess of atmospheric (with the possible exception of the second step of the mode of practice described in Example 4), and may be as high as practicable.

Either liquid or vapor phase may be practiced, and this disclosure is specifically to be read into all examples. Non-inventive skill will enable those acquainted with the art to coordinate temperatures within the range disclosed with relatively moderate pressures in order to provide vapor phase practice. When employing vapor phase operation and processing any of the feed stocks previously described, definite periods falling within the limits previously disclosed will provide specific gravities and aromatic percentages shown in the foregoing.

One phase or various phases of one example may be substituted for a phase or various phases of another example where the substitution is obviously workable.

It is to be strictly understood that all temperatures, pressures and periods of treatment shown in the examples are for purposes of illustration only.

Intermittent or continuous operation, or a combination thereof, may be practiced in the instant process, and those skilled in the art can apply this to our invention without recourse to inventive skill.

The instant process is carried on in the presence of an extraneous gas, and certain toxicity induction benefits will flow from the employment of either a reactive or non-reactive gas. Among such gases may be mentioned hydrogen, water gas, carbon monoxide, carbon dioxide, methane and its homologues, various saturated and unsaturated gases resulting from the cracking of hydrocarbons, and nitrogen, separate or in admixture. The extraneous gas or gases employed may represent a partial pressure in the process varying over a very wide range. As an example, but not as a restriction, the partial pressure of the extraneous gas or gases may be 5-50%, but it is to be strictly understood that this statement is for purposes of illustration only.

Minor changes within the scope of the appended claims may be made without departing from the spirit of the invention.

We claim:

1. In the induction of toxicity to wood destroying fungi into a mixture of petroleum fractions boiling preponderantly above 270° C., character-

13

ized by inherent but inhibited toxicity and a substantial percentage of materials of ring structure content, the process which comprises: subjecting said material at superatmospheric pressure in the presence of a non-oxidizing gas of extraneous source to a temperature selected between the limits of about 350-600° C.; unveiling toxicity in the material under treatment by carrying on the process for a period not substantially in excess of about two hours, the period being so selected with reference to the chosen temperature and pressure as to jointly provide in the beneficiation newly formed materials boiling below 210° C., a percentage of aromatics in the fractions boiling between 210-355° C. not substantially less than about 70%, and a specific gravity in the overall fractions of the material boiling between 210-355° C. falling between the limits shown in the appended tabular data:

Fractions	Low Limit	High Limit
210-235° C.	0.9506	0.9942
235-270° C.	0.9941	1.0245
270-315° C.	1.0159	1.0575
315-355° C.	1.0546	1.1175

whereby to provide a material having induced toxicity to wood destroying fungi.

2. The process of claim 1 with inclusion of segregating from the beneficiated material an oil of the wood preservative type characterized by induced toxic properties, boiling preponderantly between about 210-355° C. and having at least about 15-20% residual material boiling above 315° C.

3. In the induction of toxicity to wood destroying fungi into a mixture of petroleum fractions boiling preponderantly above 270° C., characterized by inherent but inhibited toxicity and a substantial percentage of materials of ring structure content, the process which comprises: partially unveiling toxicity in the named materials by subjecting same at superatmospheric pressure in the presence of a non-oxidizing gas of extraneous source to a temperature selected between the limits of about 350-600° C. whereby to provide an overall-beneficiation having relatively high and low toxicity in the materials boiling below and above 270° C., respectively; segregating at least a portion of the materials of relatively low toxicity boiling above 270° C. and subjecting same at superatmospheric pressure to a temperature between the limits above named; securing induced toxicity in a relatively high degree in the materials under treatment by carrying on the process in both periods of treatment for a total time not in excess of about two hours, the periods in each step being so selected with reference to the chosen temperatures and pressures as to provide newly formed materials boiling below 210° C., a percentage of aromatics in the fractions boiling between 210-355° C. not substantially less than 70%, and a specific gravity in the overall fractions of the material boiling between 210-355° C. falling between the limits shown in the appended tabular data:

Fractions	Low Limit	High Limit
210-235° C.	0.9506	0.9942
235-270° C.	0.9941	1.0245
270-315° C.	1.0159	1.0575
315-355° C.	1.0546	1.1175

whereby to provide materials having induced toxicity to wood destroying fungi; and commingling the segregations above named to provide an

14

overall oil of induced toxic properties, and containing fractions essential in an acceptable preservative impregnant.

4. The process of claim 3 with inclusion of segregating from the beneficiated material an oil of the wood preservative type characterized by induced toxic properties, having at least about 15-20% residual matter boiling above 315° C., and boiling preponderantly between about 210° C. and 355° C.

5. In the induction of toxicity to wood destroying fungi into a mixture of petroleum fractions boiling preponderantly above 270° C., characterized by inherent but inhibited toxicity and a substantial percentage of materials of ring structure content, the process which comprises: subjecting said material at a relatively high pressure in the presence of a non-oxidizing gas of extraneous source to a temperature selected be-

20 between the limits of about 350-600° C. for a period not in excess of about one hour; thereafter subjecting the heat treated material substantially in entirety to a relatively low pressure without a substantial reduction in temperature

25 for a period not in excess of about 30 minutes; unveiling toxicity to a relatively high degree in the material under treatment by carrying on the two-stage process for periods falling within the limits above named, the periods being so selected with reference to the chosen temperature and pressure as to jointly provide newly formed ma-

30 terials boiling below 210° C., a percentage of aromatics in the fractions boiling between 210-355° C. not substantially less than about 70%, and a specific gravity in the overall fractions of the material boiling between 210-355° C. falling be-35 tween the limits shown in the appended tabular data:

Fractions	Low Limit	High Limit
210-235° C.	0.9506	0.9942
235-270° C.	0.9941	1.0245
270-315° C.	1.0159	1.0575
315-355° C.	1.0546	1.1175

45 whereby to provide a material of increased toxicity to wood destroying fungi.

6. The process of claim 5 with inclusion of segregating from the beneficiated material an oil of the wood preservative type characterized by induced toxic properties, boiling preponderantly between 210° C. and 355° C., and having at least about 15-20% residual materials boiling above 315° C.

55 7. In the induction of toxicity to wood destroying fungi into a mixture of petroleum fractions boiling preponderantly above 270° C., characterized by inherent but inhibited toxicity and a substantial percentage of materials of ring structure content, the process which comprises: subjecting said material at superatmospheric pressure in the presence of a non-oxidizing gas of extraneous source to a relatively low temperature selected between the limits of about 350-600 ° C. for a

60 period not in excess of about one hour; thereafter subjecting the heat treated material substantially in entirety at superatmospheric pressure to a relatively high temperature for a period not substantially in excess of about one hour; unveiling toxicity in the material under treatment by carrying on the two-stage process for periods falling within the limits above named, the periods being so selected with reference to the chosen temperatures and pressures in the

65 70 two steps as to jointly provide newly formed ma-

15

aterials boiling below 210° C., a percentage of aromatics in the fractions boiling between 210-355° C. not substantially less than about 70%, and a specific gravity in the overall fractions of the material boiling between 210-355° C. falling between the limits shown in the appended tabular data:

Fractions	Low Limit	High Limit
210-235° C.	0.9506	0.9942
235-270° C.	0.9941	1.0245
270-315° C.	1.0159	1.0575
315-355° C.	1.0546	1.1175

whereby to provide a material of increased toxicity to wood destroying fungi.

8. The process of claim 7 with inclusion of segregating from the beneficiated material an oil of the wood preservative type characterized by induced toxic properties, boiling preponderantly between 210° C. and 355° C., and having at least about 15-20% residual materials boiling above 315° C.

9. As a wood preserving impregnant a hydrogenated petroleum oil having at least about 15-20% residual materials boiling above 315° C. and boiling preponderantly between 210-355° C. which contains not less than about 70% aromatics, the fraction 210-235° C. of which has a specific gravity falling between the limits of about 0.9506 and 0.9942, the 235-270° C. fraction of which has a specific gravity falling between the limits of about 0.9941 and 1.0245, the fraction 270-315° C. of which has a specific gravity falling between the limits of about 1.0159 and 1.0575, and the fraction 315-355° C. of which has a specific gravity falling between the limits of about 1.0546 and 1.1175.

10. As a wood preserving impregnant a hydrogenated petroleum oil having at least about 15-20% residual materials boiling above 315° C. and boiling preponderantly between 210-355° C. which contains not less than about 70% aromatics, the 235-270° C. fraction of which has a specific gravity falling between the limits of about 0.9941 and 1.0245, the fraction 270-315° C. of which has a specific gravity falling between the limits of about 1.0159 and 1.0575, and the fraction 315-355° C. of which has a specific gravity falling between the limits of about 1.0546 and 1.1175.

11. As a wood preserving impregnant a hydrogenated petroleum oil having at least about 15-20% residual materials boiling above 315° C. and boiling preponderantly between 210-355° C. which contains not less than about 70% aromatics, the fraction 270-315° C. of which has a specific gravity falling between the limits of about 1.0159 and 1.0575, and the fraction 315-355° C. of which has a specific gravity falling between the limits of about 1.0546 and 1.1175.

16

12. In the induction of toxicity to wood destroying fungi into a mixture of petroleum fractions boiling preponderantly above 270° C., characterized by inherent but inhibited toxicity and a substantial percentage of materials of ring structure content, the process which comprises: subjecting said material at superatmospheric pressure in the presence of a non-oxidizing gas of extraneous source to a temperature selected between the limits of about 350-600° C.; unveiling toxicity in the material under treatment by carrying on the process for a period not in excess of about one hour the period being so selected with reference to the chosen temperature and pressure as to jointly provide newly formed materials boiling below 210° C., a percentage of aromatics in the fractions boiling between 210-355° C. not substantially less than about 70%, and a specific gravity in the overall fractions of the material boiling between 210-355° C. falling between the limits shown in the appended tabular data:

Fractions	Low Limit	High Limit
210-235° C.	0.9506	0.9942
235-270° C.	0.9941	1.0245
270-315° C.	1.0159	1.0575
315-355° C.	1.0546	1.1175

30 whereby to provide a material of increased toxicity to wood destroying fungi; and protecting the induced toxicity by shock quenching the overall beneficiation.
